(57) **CLAIM**

The ornamental design for a cell phone stand, as shown and described.

DESCRIPTION

FIG. 1 is a top perspective view of a cell phone stand, showing my new design;

FIG. 2 is a bottom perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken line showing of a cell phone in FIG. 1 depicts environment for the cell phone stand that form no part of the claimed design.

1 Claim, 7 Drawing Sheets
